HYDRAULIC LASH ADJUSTER

Ronald K. Evans, Birmingham, Mich., assignor to General Motors Corporation, Detroit, Mich., a corporation of Delaware

Application January 20, 1955, Serial No. 482,978

17 Claims. (Cl. 123—90)

This invention relates to poppet valve operating mechanisms for internal combustion engines and the like utilizing rockers for transmitting valve opening and closing movements to and from the valve, and particularly to a mounting for such a rocker which automatically adjusts its fulcrum to compensate for wear and other factors tending to affect the lash or operating clearance between the rocker and other parts drivingly associated with it.

One of the principal objects of the invention is to improve such mechanisms by arranging the rocker to be carried by a stud extending through it from the engine cylinder head or other fixed part of the engine, the engine end of the stud carrying a plunger whose movement toward the rocker is cushioned by a body of oil in a dash pot rigid with the cylinder head.

Additional objects of the invention are to provide an improved lash adjuster adapted for mounting a rocker in the aforementioned manner, and to provide a novel means of supplying engine lubricating oil to the oil cushion chamber of such a lash adjuster.

The means by which these and other objects of the invention are attained will be clearly apparent from the following description, having reference to the drawings wherein:

Figure 1 is a transverse view through a portion of a V-type internal combustion engine incorporating a rocker hydraulic lash adjuster mechanism in accordance with the invention.

Figure 2 is an enlarged cross-sectional view of the lash adjuster mechanism and certain of its associated engine parts as shown in Figure 1.

Figures 3, 4 and 5 show successive modifications of the lash adjusting mechanism.

Referring in detail to Figures 1 and 2 of the drawings, there is shown an engine frame member including a crankcase 1 of conventional V-type having a cylinder head for each bank, one of which is indicated at 2. An engine driven cam 3 drives the tappets 4, each of which is connected by a push rod 5 and a valve rocker 6 to actuate a poppet valve 7. As shown, the rocker 6 is of upwardly dished configuration and has its respective ends overlying the upper ends of the push rod 5 and the stem of the valve 7, each of which protrudes above the cylinder head 2. The dished shape of the rocker serves to conduct engine lubricating oil fed to it through the push rod and tappet which are made hollow for this purpose, the tappet being slidably mounted in the crankcase and having registering openings 4' communicating with the oil pressure gallery 8. The upper end of each push rod has a port 9 registering with the port 10 extending through the end of the rocker, and intermediate its push rod end and the stem of the valve 7 the rocker is provided with a spherical bearing surface 11 to which the oil flows from the port 10. Excess oil is normally supplied through the push rod in the manner stated so as to overflow the valve end of the rocker and effect lubrication of its valve actuating surface 12. Centrally of the rocker bearing surface 11 is an

aperture 13 through which extends a stud 14 having a rocker journalling member 15 secured at its upper end by suitable means such as a nut 16. The lower face of the journalling member 15 is also made spherical to conform with the rocker bearing surface 11, except a relief groove 17 may be provided in the journalling member to ensure a substantial drainage of oil through the rocker aperture 13 during operation. The valve 7 has its stem reciprocally guided in the cylinder head to open with each lift stroke of the cam 3, there being the usual valve return spring 17' secured to the upper end of the valve stem and reacting against the cylinder head.

As best shown in Figure 2, the cylinder head is provided with an internally threaded opening 18 below the rocker, and screwed into this opening is a dash pot in the form of a generally upright cup-shaped cylinder 19 into which the lower end of the stud 14 extends. The bore 20 of this cylinder is substantially larger than the periphery of the stud whereby a pressure chamber 21 is formed between them. Slidably fitting this bore 20 and defining the lower end of the pressure chamber 21 is a plunger 22 formed in part by an upright cup-shaped member whose end wall 23 is apertured to embrace the stud 14 and which rests on a flange 24 formed on the lower end of the stud. Completing the plunger 22 is a gasket 25 which seals against the escape of oil between the plunger member end wall 23 and the flange 24. The stud 14 does not extend into abutment with the cylinder end wall 26 but is separated axially therefrom to provide an oil reservoir 27 between them. A guide sleeve 28 slidably supports the stud 14 within the cylinder and is, in turn, supported by a flange 29 on this guide sleeve which overlies the open end of the cylinder. A gasket 30 may be provided between this flange and the cylinder open end, as shown, for sealing purposes at this point. The guide sleeve is secured against movement outwardly of the cylinder by a hollow nut 31 which is screwed on to the threaded upper end of the cylinder and has a shoulder 32 which clampingly engages the guide sleeve 28. This flange 29 also constitutes a wall defining the upper end of the pressure chamber 21, and has an oil passage 33 extending through it and counterbored at its lower end to receive and provide a seat for a ball check valve 34. A compression spring 35 acts between the plunger end wall 23 and this fixed upper wall or flange 29 to bias the stud and plunger inwardly of the cylinder 19, the upper end of the spring 35 seating against a washer 36 whose outer diameter is sufficiently large to partially underlie the counterbored lower end of the passage 33 and serve as a retainer limiting opening travel of the ball check valve 34. The upper face of the guide sleeve flange 29 is relieved by a transverse slot or groove 37 which connects the upper end of the passage 33 with the periphery of the stud 14. The interior of the hollow nut 31 above the guide sleeve flange 29 forms an upper oil reservoir 38 into which oil is received by drainage through the rocker opening 13. An annular filter element 39, pressed into the hollow nut against the flange 29, is provided to prevent any foreign particles being carried into the groove 37 with the oil draining from the rocker. The upper and lower reservoirs 38 and 27 are interconnected by longitudinally and transversely drilled passages 40 and 41 in the stud 14, with registry of the transverse passages 41 with the groove 37 at all times being ensured by an annular groove 42 encircling the stud at this point.

During operation, with each lift stroke of the cam 3 its motion is transmitted through the tappet 4, push rod 5 and rocker 6 to open the valve against the valve return spring 17'. The resultant upward thrust of the rocker against its journalling member 15 tends to move the stud 14 outwardly of its cylinder 19. Although this movement

of the stud is resisted by the spring 35, the strength of the spring 35 is insufficient to axially support the stud, and the main opposition to such movement of the stud is instead effected by entrapment of oil under compression in the pressure chamber 21, the check valve 34 moving to its seated position closing the passage 33 in the flange 29. The pressure thus exerted on the oil in this chamber results in a certain amount of relatively slow leakage therefrom between the sliding surfaces of the plunger member 22 and the cylinder bore 20, and between the guide sleeve 28 and the stud 14, the former of such leakage oil entering the lower reservoir 27 and the other entering the upper reservoir 38 by way of the collecting groove 42 to the transverse groove 37. As the portion of the upper reservoir 38 constituted by the transverse groove 37 is normally maintained full of oil, such leakage oil flowing thereto from the pressure chamber is transferred via the drilled passages 41 and 40 to the lower reservoir 27. After the engine valve 7 reaches its fully open position and begins its return to its seat with continued rotation of the cam 3 the oil pressure within the chamber 21 and the leakage of oil therefrom to the reservoirs, of course, continues until the engine valve reaches its fully closed position. At this point in the cycle the plunger return spring 35 takes up its function of returning the rocker fulcrum axis to its initial position by moving the stud 14 downwardly into the lash adjuster cylinder 19. As this action takes place the resultant drop in oil pressure within the chamber 21 allows the check valve ball 34 to open the passage 33, permitting oil to flow into the pressure chamber in replenishment of that which was lost out by leakage during the lift and return strokes. The action described is repeated for each valve opening and closing cycle, and because there is little opportunity for oil to escape past the filter 39 such replenishment of the pressure chamber with oil as takes place from the groove 37 of the upper reservoir is substantially equalized by replenishment of this groove 37 with oil from the lower reservoir 27 via the drilled passages 40 and 41. Accordingly, a recirculating oil flow action takes place within the lash adjuster which is substantially the equivalent of that occurring in the so-called "self-contained" type of valve lash adjusters which have no external fluid supply. Such replenishment as may be needed is provided for by delivery of engine lubricating oil into the hollow nut through drainage from the rocker opening 13. Due to this drainage from the rocker the hollow nut 31 is supplied with sufficient oil at all times during engine operation to cover the filter element 39 with oil to a sufficient height to overflow the upper end of the nut 31 and thereby carry away the greater portion of foreign particles which might otherwise have opportunity to pass through the filter element and contaminate that oil recirculating between the pressure chamber 21 and the lower reservoir 27.

The arrangement described thus serves the very desirable purpose of maintaining the lash or operating clearance in the valve train at a minimum in substantially the same manner as conventional hydraulic valve lifters which move with the reciprocating parts, and is particularly adapted to mounting of valve rockers individually on studs supported from the cylinder head or other fixed frame portion of the engine.

The form of the invention shown in Figure 3 operates in substantially the same manner, differing principally in that only a single leakage path is provided for oil escaping from the pressure chamber 21 during the cam lift stroke. Such single leakage path is provided between the guide sleeve 28 and the stud 114, the plunger member 122 being made of a resilient material such as soft synthetic rubber which effectively seals the stud to the bore 20. With this arrangement only the internal wall of the guide sleeve and the external surface of the stud need be machined to the very close tolerances necessary to control the rate of "leakdown" when the rocker thrust is being supported by the lash adjuster stud. To ensure against too rapid a delivery of leakage oil into the upper

reservoir groove 37 from where it might tend to flow through the filter 39 and be contaminated with foreign particles, the stud 114 is provided with a second oil collecting groove 142 and transverse passage 141 which connect with the longitudinal passage 40 in the stud.

The Figure 4 modification differs essentially from that of Figure 2 only in the upper reservoir 38 being formed by an integral enlarged extension 131 of the cylinder 119, instead of a separate hollow nut 31 as shown in Figures 2 and 3. The guide sleeve flange 29 in this modification is press fitted into the lower end of this cylinder extension 131 to hold it in place.

In Figure 5 a somewhat different stud and plunger construction is shown, the stud 214 having its portion below the rocker expanded to slidably embrace the lash adjuster cylinder 219 which is of downwardly presenting cup shape and has its lower end threadedly anchored in the cylinder head 200. The cylinder 219 extends only partially into the expanded portion of the stud, defining a reservoir 238 between them. The cylinder head is formed with a pocket 240 surrounding the expanded cylinder end portion of the stud into which oil may drain from the rocker oil system, and the side wall of the stud above the cylinder 219 is provided with a port 241 connecting this pocket with the reservoir 238. The reservoir 238 is also open to atmosphere through an axially drilled passage 242 extending through the upper end of the stud. Adjacent the lower end of the stud its side walls are provided with diametrically opposite openings 243, and aligned with these openings are somewhat larger diametrically opposite openings 244 through the side walls of the cylinder 219. A cross pin 245 substantially smaller than the stud openings 243 extends through both sets of aligned openings and serves as an abutment for a plunger 246 which has a close sliding fit in the bore 220 of the cylinder. Between the upper end of this plunger and the end wall 229 of the cylinder is formed the oil pressure chamber 221, which is connected with the reservoir 238 by a cylinder end wall passage 233. Compressed between the wall 229 and the plunger 246 is a plunger return spring 235 whose upper end seats against a perforated cage 236 retaining and limiting opening travel of the ball check valve 34. A baffle 247 carried by the stud adjacent the open upper end of the cylinder head pocket 240 serves to collect any foreign particles carried in to the retainer with the oil draining in from the rocker. The operation of this form of the invention is fundamentally the same as that previously described with respect to Figures 2-4, oil being permitted to leak past the plunger 246 from the pressure chamber 221 at a relatively slow rate while the engine valve is open and such leakage oil being replenished from the reservoir 221 via passage 233 during that portion of the cycle when the engine valve is seated and the thrust load on the rocker is removed. By reason of the thrust load on the plunger always being in the same direction both during the period when the engine valve is open as well as during the period when the engine valve is closed, there is no lost motion of the cross pin 245 relative to the stud. The increased clearance which the cross pin has in the cylinder side wall openings 244 accommodates the relative axial movement of the stud in the cylinder. With the cylinder 219 securely anchored by its threaded connection to the engine cylinder head it will be appreciated that the cross pin serves to lock the stud from rotating during initial adjustments of the nut 16 in setting the rocker to its proper height and within the range of automatic adjustment for which the lash adjuster is designed.

It is appreciated that various minor changes in the construction and arrangement of the parts will readily suggest themselves to those skilled in the art without departing from the spirit and scope of the invention as hereinafter defined.

I claim:

1. In combination with a valve rocker, supporting and journaling means therefor including an engine frame

member, a dash pot rigid with the frame member, plunger means operable in said dash pot having a portion extending through the rocker in a direction transverse to the rocker fulcrum axis, coacting bearing surfaces on the rocker and the extended portion of the plunger, a passage for introducing fluid into said dash pot, a resilient member biasing said plunger means outwardly of said dash pot, and a check valve accommodating flow of fluid through said passage in the direction inwardly of the dash pot and preventing flow therethrough in the opposite direction.

2. In a support for a rocker having an aperture extending therethrough normal to its fulcrum axis, a stud adapted to extend through said aperture and accommodate the oscillatory movement of the rocker to be supported, said stud having a bearing surface adjacent one of its ends for journaling said rocker movement, the opposite end of said stud having a plunger fixed thereon, a cylinder slidably supporting said plunger and defining a fluid pressure chamber adjacent the rocker side of the plunger, means including a one-way valve controlled passage for supplying fluid to said chamber, a wall defining the extremities of said chamber nearest the rocker, and a spring biasing the plunger in the direction away from said wall.

3. In a valve operating mechanism for an engine or the like, a rocker, supporting means for the rocker including a fixed engine frame member, a cylinder fixed to the frame member having its axis generally normal to the fulcrum axis of the rocker, a transverse wall fixed to the cylinder and cooperating with the side walls thereof in defining a fluid pressure chamber, a plunger slidably fitting the cylinder side walls and defining the end of said chamber remote from said transverse wall, said transverse wall having an opening, said plunger having a stud portion extending through and closely fitting said opening, said rocker having an aperture loosely embracing the stud portion with sufficient clearance to accommodate rocking movement of the rocker during valve opening and closing, a bearing on the stud portion journaling the rocker in its rocking movement, a compression spring in said chamber interposed between said transverse wall and said plunger, said cylinder having a portion intermediate said transverse wall and the frame member cooperating with said stud portion in defining a fluid reservoir, a passageway connecting said reservoir and chamber, and a valve operative to open and close said passageway in response to decreased chamber fluid pressure resulting from movement of the plunger by the spring and increased chamber fluid pressure resulting from movement of the plunger against the spring, respectively.

4. In a valve operating mechanism for an engine or the like, a rocker, supporting means for the rocker including a fixed engine frame member, a cylinder fixed to the frame member having its axis generally normal to the fulcrum axis of the rocker, a transverse wall fixed to the cylinder and cooperating with the side walls thereof in defining a fluid pressure chamber, a plunger slidably fitting the cylinder side walls and defining the end of said chamber remote from said transverse wall, said transverse wall having an opening, said plunger having a stud portion extending through and closely fitting said opening, said rocker having an aperture loosely embracing the stud portion with sufficient clearance to accommodate rocking movement of the rocker during valve opening and closing, a bearing on the stud portion journaling the rocker in its rocking movement, a compression spring in said chamber interposed between said transverse wall and said plunger, said cylinder having a portion on the opposite side of the plunger from the rocker defining a first fluid reservoir and a portion intermediate said transverse wall and the rocker defining a second fluid reservoir, a passageway connecting said second reservoir and chamber, a valve at the chamber end of said passageway movably responsive in an opening direction to the fluid pressure in the second reservoir and in a closing direction to the fluid

pressure in the chamber, and a passageway connecting said first and second reservoirs for transferring fluid therebetween in response to relative axial movements of the plunger and cylinder.

5. The invention defined in claim 4, together with a source of fluid under pressure and driving means for said rocker including a hollow push rod in fluid communication with said source, said rocker and push rod having coacting bearing surfaces with mutually registering ports and a passageway in said rocker connecting its said port with its said aperture.

6. The combination with an engine cylinder head and a poppet valve operating train including a valve stem reciprocable in the head and a reciprocably driven push rod, both terminating above the head, a rocker mechanically interconnecting the push rod and valve stem, and rocker mounting means including a stud extending through the rocker from the cylinder head, of means for thrustably supporting and axially adjusting said stud relative to the cylinder head to automatically compensate for changes in the operating length of said train, said last named means including a generally cup-shaped engine oil receiving member fixed to the cylinder head and having a bore embracing the cylinder head end of said stud, plunger means on said stud slidably fitting said bore, an annular member fixed to said cup-shaped member below the open end thereof and slidably fitting the stud above said plunger means, said annular member having an oil passage therethrough connecting the interior of said bore above the plunger means with the interior of the cup-shaped member above the annular member, a check valve at the bore end of said passage preventing oil flow therethrough from below the annular member while accommodating flow in the opposite direction, a spring compressed between said plunger means and annular member for urging the stud toward the cylinder head.

7. The combination with an engine cylinder head and a poppet valve operating train including a valve stem reciprocable in the head and a reciprocably driven push rod, both terminating above the head, a rocker mechanically interconnecting the push rod and valve stem, and rocker mounting means including a stud extending through the rocker from the cylinder head, of means for thrustably supporting and axially adjusting said stud relative to the cylinder head to automatically compensate for changes in the operating length of said train, said last named means including a generally cup-shaped engine oil receiving member fixed to the cylinder head and having a bore embracing the cylinder head end of said stud, a flange on the cylinder head end of the stud, a cup-shaped plunger embracing the stud above said flange and slidably fitting said bore, a guide sleeve slidably fitting the stud above said flange and extending into said plunger, said guide sleeve having a flange at its upper end overlying the upper end of said cup-shaped member, a hollow nut screw threaded to the upper external periphery of the cup-shaped member and clamping said guide sleeve flange to the upper end of said cup-shaped member, a coil compression spring embracing said guide sleeve and seated at its opposite ends against the end wall of the plunger and said guide sleeve flange, said guide sleeve flange having an oil passage therethrough connecting the interior of said bore above the plunger with the interior of the hollow nut above the guide sleeve flange, a check valve at the bore end of said passage preventing oil flow therethrough from below said guide sleeve flange while accommodating flow in the opposite direction, and an annular filter extending between the external periphery of the stud above said guide sleeve flange and the internal periphery of said nut through which engine lubricating oil may be introduced to the upper end of said passage.

8. In a hydraulic valve lash adjuster for an over-head valve type internal combustion engine or the like having a valve rocker mounted on a stud extending through the rocker from the head, a rocker mounting stud having a

plunger part fixed thereto adjacent the head end of the stud, a cylinder part slidably supporting the plunger part and having first and second portions cooperating respectively therewith to define an oil cushion chamber between the plunger part and the rocker and a reservoir for oil to be supplied to said chamber, a spring biasing the plunger part in the direction to enlarge said chamber, passage means providing for flow of oil from said reservoir to said chamber, and a check valve operative in response to increased pressure in said chamber resulting from plunger movement against said spring to prevent said oil flow.

9. The invention defined in claim 8, wherein said cylinder part and stud have slidably interfitting surfaces between said chamber and the rocker defining a leakage path for oil escaping from the chamber, said stud having an oil leakage collecting groove in its said surface and a passage connecting said groove with said reservoir.

10. The invention defined in claim 9, wherein said cylinder part includes a wall defining the rocker end of said chamber and having a skirt portion depending into said chamber and defining the said cylinder part surface, said wall having an opening extending therethrough longitudinally of the stud and defining in part said passage means, said check valve being located at the chamber end of said opening.

11. In combination with an engine cylinder head having an opening therethrough for a poppet valve stem to be operated by a rocker spaced above the cylinder head, and a second opening laterally spaced from said first opening, said second opening being internally threaded, an upwardly open dash pot member having a reduced lower portion with external threads engaging said internal threads and a shoulder seated against the upper surface of the head surrounding said second opening, said dash pot having an axially extending bore and an upwardly presenting internal shoulder above said bore, a fixed guide sleeve in said dash pot spaced radially from said bore and having an external flange sealingly engaging said shoulder, a stud slidably fitting said sleeve and extending outwardly of said dash pot, a valve rocker having an opening surrounding the stud above the dash pot with sufficient clearance to accommodate valve operating movement of the rocker, rocker journaling means on the stud above the rocker, bearing means on the rocker adjacent said opening engaging said journaling means, a compression spring within said bore and reacting against said flange, a plunger on said stud slidably fitting said bore and biased by said spring in the direction away from the rocker, means for introducing hydraulic fluid to the space within said bore between said plunger and flange, said means including a passage through said flange, and a check valve at the inner end of said passage.

12. In combination with a rocker drivingly connected to oppositely reciprocating elements extending from one side thereof, rocker supporting means including a member on the opposite side journaling the rocker for oscillation about its fulcrum axis and a hydraulic lash adjuster located on said one side of the rocker between said elements, said lash adjuster including a hydraulically cushioned member thrustably supporting said journaling member.

13. In combination with a rocker for transmitting motion between oppositely reciprocating driving and driven elements, rocker supporting means including a member on one side of the rocker journaling the rocker

for oscillation about its fulcrum axis and a hydraulic lash adjuster located on the opposite side of the rocker from said member, said lash adjuster including a hydraulic cushion chamber and a plunger member in said chamber having a portion extending through the rocker and thrustably supporting said journaling member.

14. In combination with a rocker for transmitting motion between oppositely reciprocating elements, rocker supporting means including a member on one side of the rocker journaling the rocker for oscillation about its fulcrum axis and an automatic lash adjuster located on the opposite side of the rocker from said member, said lash adjuster including a fixed member and a movable member biased from the fixed member, said journaling member being carried by said movable member.

15. In combination with a rocker having an opening extending therethrough in the thrust direction, supporting and journaling means for the rocker including a member defining a dash pot, a plunger member operable in said dash pot having a portion extending through said opening, one of said members being fixed, said rocker and the other of said members having coating bearing surfaces defining the rocking axis of the rocker, and one-way passage means for introducing hydraulic fluid into said dash pot behind the plunger member.

16. In combination with a rocker having an opening extending therethrough in the thrust direction, supporting and journaling means for the rocker including a fixed support, a first member extending through said opening with sufficient clearance to accommodate rocking movement of the rocker, a second member telescopically associated with said first member, said members having endwise facing surfaces defining a fluid pressure chamber therebetween, one of said members being anchored to said support, said rocker and the other of said members having coating bearing surfaces defining the rocking axis of the rocker, and one-way passage means for introducing fluid into said pressure chamber.

17. Supporting and journaling means for a rocker of the stud mounted type which has an opening extending therethrough in the thrust direction, comprising a first member provided with a surface defining one end of a fluid pressure chamber and having a stud portion extending generally normal to said surface for passage through said opening, a second member telescopically associated with said first member and defining the opposite end of said chamber, one of said members having a bearing surface adapted to journalably engage the rocker adjacent said opening and define the rocking axis of the rocker, the other of said members having surfaces slidably supporting said one member for movement axially of said stud portion, and passage means for introducing fluid into said chamber and restricting its return therefrom.
